UNITED STATES PATENT OFFICE.

MANNING FORCE HATCHER, OF BROOKLYN, NEW YORK.

MARBLE-CUTTING MACHINE.

SPECIFICATION forming part of Letters Patent No. 416,164, dated December 3, 1889.

Application filed January 12, 1889. Serial No. 296,036. (No model.)

To all whom it may concern:

Be it known that I, MANNING FORCE HATCHER, a citizen of the United States, residing at Brooklyn, in the county of Kings and State 5 of New York, have invented certain new and useful Improvements in Marble-Cutting Machines; and I do hereby declare the following to be a full, clear, and exact description of the invention, such as will enable others skilled 10 in the art to which it appertains to make and use the same.

My invention relates to machines for cutting and shaping marble, slate, or any soft stone; and it consists in certain mechanical 15 devices hereinafter more fully described, and pointed out in the claims.

Figure 1 is an elevation view of the machine, showing parts thereof in vertical section. Fig. 2 is a plan or top view of the machine and shows in section a portion of the frame. Figs. 3, 4, 5, 6, 7, and 14 are views 20 showing more in detail various parts of the mechanism. Figs. 9, 10, 11, 12, 13, and 15 are views showing more in detail the cutting- 25 tools used; and Fig. 8 is a plan view of gearing, showing how the power is applied which produces the movement of the various parts, and also showing in section a portion of the frame.

30 A, Figs. 1 and 4, is the bed or frame of the machine, formed of two parts bolted together, one of which turns upward, forming an arm for the purpose of supporting the driving and cutting mechanism, while upon the other rests 35 that portion of the mechanism which is designed to carry the material to be shaped.

The power which moves the various parts 40 of this machine is communicated from an engine in the usual way by means of a belt passing over one of the pulleys S, the large or small one being used, according to the rate of speed desired. These pulleys are provided with the usual clutches for throwing them in or out of gear with the driving mechanism, 45 and when either is in gear therewith it turns the shaft T, which is supported by arms extending upwardly from the arm portion of the bed or frame A. At the extremity of the arm portion of A a perpendicular shaft W is 50 supported and is capable of adjustment to any desired height by any suitable means.

This shaft receives its power from the shaft T by means of the miter-gears V.

Various cutting-tools, depending upon the character of the design to be produced, are 55 employed in the use of this machine; but they may all be divided into two classes—vertical or horizontal, according to the position in which they are used.

The vertical tools are connected by any 60 suitable means to the lower end of the shaft W, and consist of knives k, bound by screws in a head m. In one end of said head is a hole provided with a female screw for receiving the lower end of the shaft W, while the 65 other end is slotted longitudinally in two directions at right angles to each other, in which slots the four knives k are placed, and when properly adjusted are securely fastened by means of the screws l, which pass through the 70 ring c at such points that the ends of the screws will come in contact with the edges of the tools and bind them. The ring c is normally slightly smaller than the head m, but is placed thereon when hot, thus being held 75 firmly by the shrinking of the metal when it becomes cool.

The horizontal tools consist of knives h, which are set in the sides of the head. The head is mounted on a spindle e, held in two 80 downwardly-projecting arms of the removable holder n, Fig. 14, and is revolved by means of the power received from the vertical shaft W and communicated through the gears d, Fig. 1. The head of the horizontal tool is 85 formed of two collars, one surrounding the other. The outer one is formed in six parts or segments of a circle a' a² a³, &c., Fig. 15, two of which, a' and a², are each one-quarter of the whole, and are fastened on the inner 90 collar on opposite sides thereof by means of screws passing through the flanges g, Fig. 9, of the inner collar and the segments themselves. The four knives h are placed against the four radiating sides of these segments, 95 and in each of the two opposite spaces between the knives are placed two of the other and smaller segments of the outer collar—in the one a³ and a⁴ and in the other a⁵ and a⁶. By this arrangement the four knives are 100 placed equidistant from each other. They are held in this position by the tapered screws

i, one of which passes between the adjoining sides of a^3 and a^4 and the other between those of a^5 and a^6 , thereby causing all the parts to bind. The screws enter a sufficient 5 distance into the inner collar to hold the parts firmly. The flanges *g* on the inner collar prevent any longitudinal movement of the parts.

That portion of the machine designed to 10 carry the material to be shaped is provided with two carriages B C and a table D. The lower carriage B moves in ways to or from the operator along and by means of the screw-shaft L. The upper carriage C, supported 15 on B, moves in ways at right angles thereto by means of the screw-shaft N. The table D is supported on the carriage C and moves only therewith. The screw or main shaft L receives its power to revolve by the pulleys 20 M when in gear therewith, a straight belt running over one and a crossed belt over the other to the pulleys R on the shaft T, here- 25 fore mentioned, thereby enabling the operator to reverse the motion of the shaft L at will. The shaft N receives its power by means of the spur-wheels *t*, Fig. 8, and the miter-gears *v* from the shaft P, which receives its power from L by means of the spur-wheels *r*. On the upper table are pivoted at 30 E' and E², respectively, Figs. 2 and 5, a disk E, Fig. 6, and a quadrant F, Fig. 7, each of which is provided on the under side with a rack near the outer edge. Beneath the table D there is a lever Z, pivoted on the shaft 35 G, and having two wheels G' G² geared together. By turning the lever Z to the right or left G² can be geared with the rack on either the disk or quadrant, as may be desired. The shaft G extends through the carriage C, and beneath said carriage is provided with a worm-wheel H, which engages with the screw on the shaft I. Power is communicated to the shaft I from the main shaft L by the gears *w*, shaft J, miter-gears *s*, shaft 45 K, and gears *p*, and either the disk or quadrant may be slowly turned at will whenever G² is in gear with one or the other. By means of this mechanism for carrying the material to be operated upon it is plain that the operator can not only bring any portion of the material directly under and in connection with the cutting tools and can cause the material to move slowly along in any direction against said tools, but also, if the material be placed 55 upon the disk it can be cut in the form of a circle, or if upon the quadrant the corners of a rectangular piece can be cut to that form. It will be observed that when this last-mentioned operation is performed the machine once started will cut an exact quarter of a circle if the material be first properly adjusted on the quadrant, for the moment the quadrant has turned the material to the distance of ninety degrees it will cease to move 60 farther, because the turning power will then have reached the end of the rack on the quadrant and the quadrant will stop. On the table

D there is also a lathe A' A², which is operated by means of the spur-wheels B³ B⁴, shaft C⁵, worm-wheel D⁶, screw on shaft K, and spur-wheels *p*, one of which is on the main shaft 70 L. The lathe is used for turning posts, vases, columns, &c., and if the carriage C, on which the table D rests, be in motion at the same time that the lathe is operated a spiral may 75 be cut in or various other forms of ornamentation given to the article held in the lathe.

Each of the shafts L, K, or P is provided with one or more clutches *x*, for throwing the various parts of the mechanism in or out of 80 gear with the pulleys M, and either may be turned by hand, when desired, by removable cranks.

A circular saw *f* can be put on the spindle 85 *e* in the place of a horizontal tool whenever it becomes desirable to do so.

Having described my invention, what I claim is—

1. The combination of a bed, two carriages mounted on ways arranged at right angles to 90 each other, a disk and a quadrant carried by the upper carriage, and an arm and shaft mounted in said arm, said arm provided with a head and a suitable cutting-tool mounted in said head, substantially as described. 95

2. The combination of a bed, two carriages mounted on ways arranged at right angles to each other, a disk and a quadrant carried by the upper carriage and provided each with suitable teeth, a lever pivoted between the 100 disk and quadrant, suitable intermeshing gears carried by the lever for engaging the teeth on the disk or quadrant at will, and an arm and shaft mounted in said arm, said arm provided with a head and a suitable cutting-tool mounted in said head, substantially as 105 described.

3. The combination of a bed, two carriages mounted on ways arranged at right angles to each other, a disk and a quadrant carried by 110 the upper carriage and provided with suitable teeth, a lever pivoted between the disk and quadrant, suitable intermeshing gears carried by the lever for engaging the teeth on the disk or quadrant at will, the axis of one of the 115 gears extending through the upper carriage, a pinion mounted on the lower end of said axis, a worm-wheel engaging said pinion, means for operating said wheel, an arm, a shaft mounted in said arm, said arm provided with a head, and a suitable cutting-tool mounted in said head, substantially as described. 120

4. The combination of a bed, two carriages mounted on ways arranged at right angles to 125 each other, a disk and a quadrant carried by the upper carriage and provided each with suitable teeth, a lever pivoted between the disk and quadrant, suitable intermeshing gears carried by the lever for engaging the 130 teeth on the disk or quadrant at will, the axis of one of the gears extending through the upper carriage, a pinion mounted on the lower end of said axis, a worm-wheel engaging said

pinion, an arm, a shaft mounted in said arm and provided with a head, a suitable cutting-tool mounted in said head, suitable shafts I J K, and pinions and gears *w w* and 5 *s s*, for transmitting motion to the worm-wheel, substantially as described.

5. The combination, with the bed, carriages, disk, and quadrant, of the lever having the intermeshing gears pivoted between the disk 10 and quadrant, the axis of one of said gears extending through one of the carriages, a pinion on the lower end of said axis, a worm-wheel engaging said pinion, a shaft I, carrying the worm-wheel, a shaft K, suitably geared 15 by intervening mechanism with the shaft I, screw-threaded shafts L and N, arranged at right angles to each other and passing through some portion of each of the tables, a shaft P, suitably geared to the shaft N, gears *r r*, one

on each of the shafts L P and intermeshing, 20 gears *p*, mounted on the shafts K L and also intermeshing, and suitable clutches *x*, for throwing in and out of gear each of the shafts K, L, and P at will, substantially as described.

6. The combination of an internally-screw-threaded head *m*, having radial slots, a collar shrunk onto said head around the upper portions of the slots, and screws passing through the collar opposite the slots for holding the cutting-blades therein, substantially as described. 25

In testimony whereof I affix my signature in presence of two witnesses.

MANNING FORCE HATCHER.
